TOOL EJECTOR

Ozni E. Schauer, Cincinnati, Ohio, assignor to
The Cincinnati Bickford Tool Company, Oak-
ley, Cincinnati, Ohio, a corporation of Ohio

Application February 7, 1950, Serial No. 142,767

3 Claims. (Cl. 279—97)

1

This invention relates to automatic mechanisms known as tool ejectors of which a variety has hitherto been proposed and in part marketed. In such mechanisms the tool has a tapered shank which is mounted in a tapered bore at the end of a spindle; the bore being longer than the tool shank. In the initial nonautomatic construction, a cross-slot was provided so that the tool could be forced out by laterally driving in a wedge or drift which, by contact, with the extreme end of the tool, would displace it sufficiently to loosen it in its socket. This consumed time and tended to batter the end of the tool.

In certain of the subsequent automatic types, a camming-lever was arranged in a suitable space in the spindle and pinned to the side walls of the space; the pin acting as a fixed pivot about which the lever could be swung so as to bring a camming contour thereof into sliding contact with the tool and forcibly effect its release.

The objective of the present arrangement is to avoid all pivot pins, which are a source of weakness and some trouble to make and assemble, and in lieu thereof to provide a rocker so shaped that it requires only to be slipped in place, and which, inherently, will be more sturdy and reliable.

In the drawings, Figures 1 and 2 are similar vertical sectional assemblies; the first showing the normal relation of the parts, and the second showing the rocker tilted to discharge the tool. Figure 3 is a horizontal cross-section through plane A—A of Figure 1.

The spindle 1, which is conventionally mounted for rotation and translation in the machine frame, has the customary taper socket 2 which extends, at its upper end, from a narrow cross-slot 3. Normally, the taper-shank 4 of the tool 5, is seated in said socket and has the usual flat end 6 terminating midway the ceiling 7 and floor 8 of the slot.

Occupying this slot, is an L-shaped rocker A; the foot 10 of which is curved at its toe 11 to rest on the floor of the slot at one side of the space occupied by the tang 6 of the drill, the heel 12 of the foot likewise bears, or nearly so, on the ceiling and is curved so that the rocker may be rocked while maintaining the said relation.

The leg 9 of the rocker serves the dual purpose of enabling the rocker to be tilted and also of pushing the tang of the tool to free it. This leg extends transversely and occupies the upper

half of the slot and terminates at 12 to protrude somewhat beyond the periphery of the spindle.

The means for operating the rocker is a collar B which fits around the spindle and is caused to rotate therewith but may be vertically shifted thereon; a key 13 secured by a screw 15 and slideable in a spline-groove 14 in the spindle providing said relation. This collar B is provided with a recess 16 into which fits the extremity of the leg 9. Thus, by shifting the collar B upwardly into the position shown by Figure 1, the rocker is held out of contact with the tang 6. By shifting the collar downwardly, the leg 9 of the rocker A will be caused to press against the tang to release the tool.

The upper or normal relation of the collar to the spindle is maintained by a spring interposed between a flange 18 provided on the spindle and shoulder 19 of the collar. This relation is maintained during the translations of the spindle within its working range i. e. below the position shown by Figure 1.

To eject the tool, however, the spindle with its collar is further raised. This first brings the flange 20 of the collar impacts against a stationary portion 21 of the frame or head which arrests its further upward travel. The spindle, however, can continue and the collar, in effect, slides thereon; the spring 17 being compressed until the ultimate position as indicated by Figure 2 is attained.

The rocker A is thereby tilted down against the top of the tang and the tool is thus loosened in its socket and can be entirely withdrawn. During this tilting, the heel and toe of the foot shift laterally somewhat by reason of the contact at 22 of the sole of the foot against the side wall of the collar.

The rocker is thus in the nature of a floating element and, being devoid of any pivot pin, constitutes a sturdy construction capable of enduring long-life usage. As will be perceived, the pressure of the collar is compounded at the tang and furnishes adequate pressure to release the tool in its socket.

45 I claim:

1. A tool ejector comprising a spindle having a taper bore opening into a transverse slot; a taper shank tool within said bore and having its tang in said slot; an L-shaped one-piece rocker with said slot and having the toe of its foot normally resting on the floor of the slot and its heel closely contiguous to the roof of the slot, said rocker having a leg extending diametrically through the upper region of said slot and extruding somewhat beyond the periphery of the spindle; a col-

iar splined to said spindle and having a recess containing the extremity of the rocker leg; a spring for normally maintaining said collar in its uppermost position against a stop provided by the spindle; a stationary frame-member adapted to abut against a flange provided by said collar to limit its upward travel with said spindle and cause said collar downwardly to tilt the rocker to bring its heel against the roof of said slot and thereby eject the tool.

2. A tool ejector comprising a spindle having a taper bore opening into a transverse slot; a taper shank tool within said bore and having a tang extending into said slot; an L-shaped one-piece rocker within said slot with the toe of its foot normally resting on the floor of the slot and with its heel closely contiguous to the roof of the slot, said rocker having a leg extending diametrically through the upper region of said slot and extruding somewhat beyond the periphery of the spindle; a collar slidably mounted on said spindle and engaging the extremity of the rocker leg and normally maintained in its uppermost position relative to said spindle by a stop on said spindle; a stationary frame-member adapted to be abutted by a flange provided by said collar to limit its upward travel with said spindle and cause said collar to tilt the rocker downwardly to bring its heel against the roof of said slot and its sole against the inner periphery of the collar to bring its leg against the tang of the tool.

3. A tool ejector comprising a spindle having a taper bore opening into a transverse slot; a floating L-shaped one-piece rocker loosely mounted within said slot and having the toe of its foot nor-

5 mally resting on the floor of the slot and its heel closely contiguous to the roof of the slot, said rocker having a leg extending diametrically through the upper region of said slot and protruding somewhat beyond the periphery of the spindle; a collar mounted on and shiftable relatively to said spindle and having a recess containing the protruding extremity of the rocker leg; a spring for normally maintaining said collar in its uppermost position relative to said spindle against a stop provided by the spindle; a stationary frame-member adapted to be abutted against a flange provided by said collar to arrest its upward travel when said spindle has been 15 raised beyond its normal working-range and cause said collar downwardly to tilt the rocker to bring its heel against the roof of said slot and its leg against the top of said tang.
